UNITED STATES PATENT OFFICE.

WILLIAM H. BRADLEY, OF BELLEVUE, PENNSYLVANIA, ASSIGNOR OF ONE-FOURTH TO ALEXANDER GILLILAND, ONE-FOURTH TO WILLIAM C. BRADLEY, OF BELLEVUE, PENNSYLVANIA, ONE-EIGHTH TO M. E. WEBSTER, OF CHICAGO, ILLINOIS, AND ONE-EIGHTH TO SARA L. BRADLEY, OF ST. LOUIS, MISSOURI.

GAS-PRODUCER.

No. 838,946.

Specification of Letters Patent.

Patented Dec. 18, 1906.

Application filed February 23, 1906. Serial No. 302,327.

To all whom it may concern:

Be it known that I, WILLIAM H. BRADLEY, of Bellevue, Allegheny county, Pennsylvania, have invented a new and useful Gas-Producer, 5 of which the following is a full, clear, and exact description, reference being had to the accompanying drawings, forming part of this specification, in which—

Figure 1 is a sectional plan view of a gas-producer embodying my invention, and Fig. 10 2 is a vertical central section with the upper portion broken away.

My invention is an improvement upon the gas-producer described and claimed in my 15 Patent No. 807,594, of December 19, 1905, the object being to provide means of simple and effective character whereby the distribution of air, or air and steam, within the producer may be more thoroughly regulated and 20 controlled.

With this object in view my invention consists in the novel construction, arrangement, and combination of parts, all substantially as herein described, and pointed out in the appended claims.

In the drawings, 2 designates the masonry shell of the producer, and 3 the lining thereof. Beneath the shell 2 is a water-trough 4, adapted to contain water and to constitute a water 25 seal. Across this trough at its central portion is preferably a wall or partition 5, which is of inverted-V shape in cross-section and which is adapted to shed the ashes toward the end of the producer in the direction in which 30 the trough extends. Above this wall or partition 5 and at right angles thereto are located the wind pipes or chambers 6 and 7, supported by cross-girders 8 and perforated for the discharge of air and steam into the 35 producer.

As thus far described the construction and arrangement is similar to that shown in my said patent.

In accordance with my present invention 45 each of the wind pipes or chambers 6 and 7 is divided longitudinally throughout its length by a vertical partition-wall 9, so that each wind box or chamber consists of two entirely separate and distinct parts, both of which

have perforations leading into the producer- 50 chamber.

10 designates supply-pipes, one of which communicates with each portion of each of the wind pipes or chambers and by means of which the supply of air and air and steam delivered thereto may be separately and independently controlled.

By means of this improvement it will be apparent that the supply of air to every part of the producer may be regulated and such 60 distribution thereof obtained as will secure the most effective result in the operation of the producer.

What I claim is—

1. A gas-producer having wind-pipes extending across the chamber, each pipe comprising parallel-extending wind-chambers with air-discharge openings in their tops, and separate connections for supplying air to each of the chambers; substantially as described. 65

2. A gas-producer having wind-pipes extending across the chamber, each pipe comprising parallel-extending wind-chambers with air-discharge openings in their tops and 75 sides, and separate connections for supplying air to each of the chambers; substantially as described.

3. A gas-producer having a plurality of transverse wind-pipes therein, each pipe having a partition dividing it into parallel chambers, each chamber having top openings through its length, and separate connections for supplying air to each chamber of the wind-pipes; substantially as described. 80

4. A gas-producer having a plurality of wind-pipes extending across the producer-chamber, each pipe having an open bottom entering a water seal beneath the producer and comprising parallel-extending wind-chambers with upper air-discharge openings, and separate pipe connections for supplying air to each chamber of each pipe; substantially as described. 85

5. A gas-producer having a plurality of wind-pipes extending across the producer-chamber, each pipe having an open bottom entering a water seal beneath the producer 90

and comprising parallel-extending wind-chambers with upper air-discharge openings, pipe connections for supplying air to each chamber of each pipe, said connections being located respectively at opposite ends of the two chambers of one pipe; substantially as described.

In testimony whereof I have hereunto set my hand.

W. H. BRADLEY.
